UNITED STATES PATENT OFFICE

HAROLD M. HEGYESSY, OF ALLIANCE, OHIO

SWITCH

Application filed November 9, 1927. Serial No. 232,107.

The present invention is directed to improvements in direction signals for motor vehicles.

The primary object of the invention is to provide a device of this character so constructed that indicia upon the rear end of the vehicle will be illuminated to indicate to following traffic the intended course about to be traveled by the car, the illumination of the indicia being controlled by the steering gear of the vehicle.

With the above and other objects in view, the invention resides in the novel features of construction, formation, combination and arrangement of parts to be hereinafter more fully described, claimed and illustrated in the accompanying drawings, in which:

Figure 1 is a side elevation of an automobile showing the friction plates thereon.

Figure 2 is a front view of the switch containing casing, with the front cover removed.

Figure 3 is a sectional view on the line 3—3 of Figure 2.

Figure 4 is a view of the signal casing.

Referring to the drawings, 1 designates a casing which includes a vertical flange 2 adapted to be bolted to one of the side sills of the vehicle.

This casing has an intermediate partition wall 4 mounted therein and is formed from suitable insulating material, the bottom 5 of said casing being likewise formed from insulating material and is provided with a longitudinal slot 6, the purpose of which will be later explained. Carried by the partition 4 are outer binding posts 7—7 and an intermediate binding post 8, the former being connected with the resilient arcuate contacts

9—9, there being conducting wires 10—10 leading therefrom and connected with the bulbs, not shown, in the signal box 11 which is mounted upon the rear end of the vehicle, said box having glass panels therein bearing

indicia, such as the representation of hands, or, if desired, the words Right and Left may be used in lieu of the hands, as may suit the fancy of the manufacturer.

Connected to the post 8 is a bracket 13 and to which is connected the upper end of the

switch arm 14, said arm being movable in the slot 6 of the bottom 5.

To the lower end of the arm is connected a block 15 of suitable insulating material, the rear end of which is connected to the casing 1 by a coil spring 16. A clasp 17 is engaged with the steering rod arm 18 and to which is attached the forward end of a wire 19, the rear end thereof being secured to the forward end of the block 15. Leading from the post 8 to the ignition circuit of the vehicle is a conductor 20.

It will be obvious that when the vehicle is traveling in a straight course that the switch arm 14 will be positioned between the lower terminals of the contact strips 9—9, at which time the signal will not be illuminated. However, as soon as the car is turned to the right or left, the switch arm 14 will be moved accordingly through the medium of the arm 18 and wire 19 and will contact with one of the strips 9—9, thus closing the circuit and illuminating the signal to indicate the direction about to be traveled.

The tension of the spring 16 is such that when the vehicle is making a left hand turn the arm 14 will be drawn rearwardly for contact with a strip 9. The wire 19 will move forwardly when the vehicle is making a right hand turn, thus contacting with the other strip.

It will, of course, be understood that the signal will be placed in operation only after the ignition switch has been turned on. Thus, when the car is parked and the ignition switch is turned off, the front wheels thereof can be turned at any angle without illuminating the signal.

Should it be desired to change the throw of the switch arm 14 the clasp 17 may be adjusted vertically upon the arm 18.

Having thus described the invention I claim:

Circuit closing means for a motor vehicle signal comprising a casing having a longitudinally slotted wall, a partition adjacent the wall opposite the slotted wall, an arm pivoted at one end to the center of the partition and projecting through the slotted wall, resilient contact strips at the sides of the

arm connected at one end to the partition and curved concentric with the pivot of the arm and having their terminals spaced apart to clear the arm, binding posts forming connecting means between the pivoted arm, contact strips and partition, an element pivoted centrally to the outer end of the arm, a contractile spring connecting one end of the pivoted element with the casing, and an operating element connected to the opposite end of the said pivoted element.

In testimony whereof I affix my signature.
HAROLD M. HEGYESSY. [L. s.]
